CURTAIN HANGER

Filed Dec. 21, 1934

UNITED STATES PATENT OFFICE

2,015,815

CURTAIN HANGER

David Press, Chicago, Ill.

Application December 21, 1934, Serial No. 758,559

4 Claims. (Cl. 211—119)

This invention relates to a curtain display rack or frame and has for its object to provide an inexpensive, light, portable and convenient device for displaying either a pair or four or more so-called 5 cottage curtains, or a plurality of flat curtains, or a combination of two or more curtains with adjacently mounted valances, and is particularly adapted for use in stores and display rooms where a large number of curtains may be displayed in 10 such a way that the same may be quickly and easily removed or mounted on a rack, and if desired, mounted in natural position upon an artificial display window.

A further object of my invention is the provision of a curtain hanging device which has a convenient and downwardly extended handle formed integral with the upwardly extending hanger hook and which will permit an operator to quickly grasp, unhook, balance and/or move to any desired position the rack and attached curtains with but one hand and without the objectionable usual manual movement of portions of the curtain which usually lie upon or about the frame.

A further object of my invention is the provision of a curtain hanging rack which is adapted particularly for display of bungalow curtains in their proper and natural relative positions and which may likewise be used for suspending and displaying a single flat unhemmed curtain, either 25 of embroidery or other sensitive material, said rack being of a novel construction permitting selective mounting of adjacent curtains and/or valances.

With the above and other objects in view, as 30 will be apparent from the following specification and claims, the invention resides in the certain combination, structure and in the combination and arrangements of the parts, as will be herein-after more fully described and claimed.

40 On the drawing:

Fig. 1 is a front elevation of the preferred form of my curtain hanger.

Fig. 2 is a side elevation looking at Fig. 1 from the right thereof.

45 Fig. 3 is a cross sectional view taken on the line 3—3 of Fig. 1.

Fig. 4 is an enlarged fragmentary view taken from above on line 4—4 of Fig. 1.

50 Fig. 5 is a front elevation and partially fragmentary view of a slightly modified form of my curtain hanging rack.

Fig. 6 is an enlarged and fragmentary and cross sectional view taken on line 6—6 of Fig. 5.

55 Referring to Figs. 1 and 2, the reference numeral 10 indicates a cross bar which is usually

in horizontal position and which has integrally formed downwardly and substantially perpendicularly extending side members 11 and 12, all of which are formed of a relatively malleable but stiff metal rod or wire. The vertical member 12 extends downwardly and terminates in a horizontally extending lower cross bar 13 which is normally substantially parallel to cross bar 10 and which terminates in a loop or eyelet 14, as clearly shown in Fig. 4. An upwardly opening hook 15 is formed on the lower end of vertical side member 12 which is adapted to receive and releasably engage eyelet 14 of cross bar 13.

An important feature of my invention is the means provided for handling same, this means comprising a relatively long downwardly extending and upwardly opening U-shaped member 16, the bend 17 of the lower portion of which is substantially below the central point of my rack.

The parallel portions of said handle member 16 are secured to cross bar 10 at the points of intersection thereof preferably by welding. One of said parallel portions extends vertically to a point a short distance above cross bar 10 and terminates in a hook 18, as clearly shown in the drawing, and which permits convenient mounting or demounting of the device on a longitudinal pipe or other suitable anchoring means. An obtuse angled metal brace rod which has its ends secured by welding or the like to cross bar 10 at 30 points equi-distant from its center forms opposed braces 19 and 20. The center of said brace rod is welded to the upper hook portion 18 at the point of intersection, as clearly shown in the drawing.

35 A relatively short hook 21 is secured by welding or the like at a tube vertical to frame member 11 at a short distance below the cross bar 10. A similar hook 22 is likewise secured in opposed and corresponding position on said frame member 12, the upper portions of said hooks being bent toward their respective side frame members, as clearly indicated in Fig. 1 and for the purpose of preventing accidental removal of a cross rod to be described. A cross rod 23, best 40 shown in Figs. 1 and 3, is formed of a single piece of relatively stiff metal, and has its ends bent to form end eyelets or loops 24 and 25 respectively, the length of said cross rod 23 being such that the loops 24 and 25 will be conveniently received 50 by hooks 21 and 22 respectively. Because the upper portion of the hooks 21 and 22 are bent toward their respective vertical side frame members so that their respective openings are slightly less than the diameter of the respective loops 24 55

and 25, said loops will, when pressed downwardly, snap into engagement on said hooks and remain therein until manually removed. In actual use a hemmed curtain or pair of curtains is first mounted upon the said cross rod 23 by inserting the rod through the hem or hems thereof and thereafter the same is hung in the position indicated.

In actual practice relatively short or so-called bungalow curtains having an edge hem are adapted to be mounted upon the lower cross bar 13 by inserting the same through the hem of said curtains and thereafter hooking the free looped end upon hook 15 into the position indicated in Fig. 1.

The construction of the U-shaped handle member 16, which is formed integrally with upper hook 18 and secured at spaced apart points of intersection with cross bar 10, provides a rigid handle whereby the curtain hanger and mounted curtains may be quickly grasped by one hand of the operator and mounted and demounted upon suitable hanging means, usually a horizontal bar or pipe, this permitting quick and convenient 25 change of display and presentation to a customer.

In order to provide for mounting one or more flat unhemmed or embroidered curtains, I employ the same hanger rack as hereinbefore described except slightly modifying the same by providing and adding thereto a second cross rod 26 which is identical in construction to cross rod 23 shown in Fig. 3. Said second cross bar 26, having similar integral end loops, is adapted to be placed upon said first mentioned cross rod 23 and in engagement with the loops and into a position where it will impinge and pinch between said adjacent rods the edge of a flat curtain, drape or the like. In order to maintain said impingement and frictional contact to evenly support a hanging curtain, I provide relatively resilient metal hook-like clips 27 and 28 which have their shank portions secured on and rotatable about the cross rod 23, preferably at points adjacent its ends. The hook portions of said clips 27 and 28 are of such a size that the same will encircle and snap about the adjacent cross rod 26, as clearly shown in Figs. 5 and 6.

It will be apparent that I have provided a novel inexpensive, light and convenient construction in a curtain hanger or rack which is readily adaptable for use in connection with the display of several conventional forms of curtains and that such construction includes a handling means of novel and inexpensive construction which extends to a point near the center of the frame or rack.

I am aware that numerous details of construction may be varied through a wide range without departing from the principles of this invention, and I therefore do not desire to limit the patent granted hereon otherwise than necessitated by the prior art.

I claim as my invention:

1. A curtain display frame comprising a metal framework including an upper and a lower horizontal cross bar and downwardly extending vertical side members; a hook formed integrally with the lower end of one of said vertical side members, an eyelet formed on said lower cross bar

and engageable with said hook; an upwardly opening hook on each of said side members substantially adjacent the upper cross bar; a cross rod having looped ends releasably engageable with said last mentioned hooks; and an upwardly extending hanger hook secured to the upper of said cross bars and having its shank portion looped and extending substantially downwardly to form a relatively long U-shaped handle member, said shank portion being secured to said cross bar at 10 spaced apart points of intersection. 5

2. A curtain display frame comprising a metal framework of substantially rectangular shape and including an upper horizontal cross bar and integral downwardly extending vertical side members, one of said side members being bent at right angles to form a lower cross bar extending horizontally and substantially parallel to said upper cross bar, the other of said side members terminating in a hook, an eyelet formed on said lower horizontal cross bar and engageable with said hook; an upwardly opening hook on each of said side members substantially adjacent said upper cross bar; a cross rod having looped ends releasably engageable with said last mentioned 20 hooks; and an upwardly extending hook secured to said first mentioned cross bar and having its shank portion extending substantially downwardly and then being looped upwardly to form a relatively long U-shaped handle member, the 25 extreme end of said shank portion being secured to said cross bar at points spaced apart from said first mentioned point of secured of said hook. 30

3. In combination with a metal curtain hanger including a pair of spaced apart cross bars connected by integral substantially parallel spaced apart side members, the lower of said cross bars having one free end and a releasable connection with the lower end of one of said side members; an upwardly extending metal hook having a downwardly extending shank intersecting said upper cross bar and secured at such point of intersection, said shank extending downwardly and perpendicularly to said upper cross bar to form a relatively sharp bend at a point substantially mid-way between said cross bars, said shank thence extending upwardly and terminating at a point of intersection with said upper cross bar. 35

4. In combination with a metal curtain hanger including a pair of spaced apart cross bars connected by integral substantially parallel spaced apart side members, the lower of said cross bars having one free end and a releasable connection with the lower end of one of said side members; an upwardly extending metal hook having a downwardly extending shank intersecting said upper cross bar and secured at such point of intersection, said shank extending downwardly and perpendicularly to said upper cross bar to form a relatively sharp bend at a point substantially midway between said cross bars, said shank thence extending upwardly and terminating at a point of intersection with said upper cross bar; an upwardly opening hook on each of said side members, and a cross bar having looped ends engageable with said hooks respectively. 55 60 65
